CASE FOR A PENDANT WATCH

Raymond Musy, La Chaux-de-Fonds, Switzerland, assignor to Accurist S.A., La Chaux-de-Fonds, Switzerland

Filed Oct. 19, 1970, Ser. No. 25,542

Claims priority, application Switzerland June 11, 1970

Term of patent 14 years

Int. Cl. D10—02

U.S. Cl. D42—8

FIG. 1

FIG. 2

FIG. 3

FIG. 4

FIG. 1 is a front elevational view of a case for a pendant watch showing my new design;

FIG. 2 is a left side elevational view;

FIG. 3 is a rear elevational view; and

FIG. 4 is a top plan view with the strap and ring omitted for clarity of illustration.

I claim:

The ornamental design for a case for a pendant watch, substantially as shown and described.
